UNITED STATES PATENT OFFICE.

WILLIAM D. LUTZ, OF ALLENDALE, NEW JERSEY.

ELECTRICALLY-CONTROLLED ELEVATOR.

No. 851,682.

Specification of Letters Patent.

Patented April 30, 1907.

Application filed June 22, 1905. Serial No. 266,397.

To all whom it may concern:

Be it known that I, WILLIAM D. LUTZ, a citizen of the United States, and a resident of Allendale, in the county of Bergen and State of New Jersey, have invented certain new and useful Improvements in Electrically-Controlled Elevators, of which the following is a specification.

My invention relates to automatic elevators and especially to that class of electric elevators which are automatic in their operation and are especially adaptable for use in private houses.

The object of my invention is to provide a simplified and improved system of elevator control which may be operated without the use of the usual switches of push buttons in the hallways and which will be entirely automatic and safe in its operation.

To these ends I have provided certain novel arrangements and combinations of parts which will be described in the following specification and the novel features thereof pointed out in claims.

Referring to the drawings, Figure 1 is an elevation of an elevator mechanism and certain connected parts which I use in carrying out my invention. Fig. 2 is a sectional view of a special door lock and this figure shows certain parts of the lock which are mounted upon a door and other parts which are mounted upon a door jamb or casing. Fig. 3 is a side elevation, partly in section, of the parts shown in Fig. 2. Figs. 4 and 5 are detail views of certain parts which are within the door lock and are used in conjunction with the lock mechanism. Fig. 6 is a diagram of a preferred system of wiring for an electric elevator which embodies my invention. Fig. 7 is an elevation of the floor controller. Fig. 8 shows a preferred form of a detail of the floor controller.

Like characters of reference designate corresponding parts in all of the drawings.

10 designates an elevator car which is connected to a hoisting mechanism, 12 by means of a cable 11. The hoisting mechanism comprises a motor 13 and a winding drum 14 which may be connected together by suitable gearing within a casing 15. This mechanism may also be provided with a brake 16. A floor controller 17 is shown mounted upon the motor and this is connected to the shaft of the winding drum 14 by a chain or belt 18. 19, 19, 19 designate doors in the hatchway

which lead to the elevator car, and are provided with my improved door latch.

20 designates a controller which comprises certain switches and other apparatus for the control of the motor which will be described hereinafter.

30 designates my improved door lock with its coacting parts. Referring now to Figs. 2 and 3, I will describe the various parts of this lock. 31, 31 designate its knobs or handles. They are attached to a shaft or spindle 31A to which a cam 31B is also attached. This cam is so placed in relation to a latch 32 that the latter may be raised whenever the cam is turned to one side or the other. The latch 32 is shown as carried by a latch frame 32A which may be pivoted at 32B, and the cam 31B may engage with this frame to lift the latch. The latch is slidably mounted in the frame 32A and is provided with a spring 32C which normally keeps it in its outward position, as shown in the drawings. The outward movement of the latch is adjustably limited by nuts 32D on the inner end of the latch. The outer end of the latch is beveled, as shown, and carries a contact plate 32F which is attached to but insulated from the rest of the latch. A strip of insulating material is shown at 32E. 33 designates a lever which is arranged to be operated by a key. When a key is inserted in the lock and is turned to the right it causes the lever 33 to engage with a pin or projection 33B on the latch 32 and to thereby move the latch back against the action of the spring 32C until it releases the door. The latch may also be moved from the car by means of a handle 33C on the inside of the door. The parts of the door lock so far described are preferably mounted on or within the door itself. The other parts of the lock may be mounted on or within the door jamb or casing. They comprise a number of parts, one of which is a locking roller 34 which is carried on one of the ends of the bell-crank lever 34A which lever is pivoted at 34B. To the other end of this bell-crank lever a spring 34D is attached which tends to hold the parts in the position shown with the shorter end of the bell-crank lever resting against a stop 34E and with the locking roller moved outward into the position shown, where it is behind the latch 32. A swinging locking plate 35 which is pivoted at 35A is held against the shorter end of the bell-crank lever by a spring 35B.

100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

This locking plate is made of magnetic material and is arranged to be moved back out of engagement with the bell-crank lever by means of an electromagnet 36.

5 Above the latch 32, a circuit closer 37 is placed. This is shown in Fig. 2 and somewhat more in detail in Fig. 4. It comprises an arm 37A pivoted at 37B in a stand 37C. 37D are stationary electrical contacts supported on, but insulated from a bracket 37E. There are preferably four of these contacts, to each of which a conductor may be connected. One end of the arm 37A is directly above the latch 32 and is arranged to be engaged by 15 the latch when the latter is raised, and the other end of the arm is above the contacts 37D and is arranged to be moved down against them and to bridge and thereby electrically connect the contacts in pairs. That is 20 the two right hand contacts will be connected together and the two left hand contacts will be connected together by the arm 37A. To accomplish this, arm 37A carries two bridge pieces 37F which must be insulated from 25 each other. It is evident then that when the latch is raised the contacts just pointed out will be connected together. Two other electrical contacts 38A and 38B are also shown in the drawings in Figs. 2 and 5. 30 These are insulated from the rest of the lock and from each other as shown at 38C. They are so placed that when the latch 32 is in locking position, its metallic face 32F will engage with and electrically connect the two 35 contacts 38A and 38B. It is important that the relative position of the parts just described shall be such that the face of the latch shall not touch these two contacts until the latch is behind the locking roller 34 and 40 the stationary locking plate 39 which I will now point out. This locking plate 39 is situated below and may be slightly in advance of the locking roller 34 and is for the purpose of engaging with the latch 32, when the latter 45 is in the position shown in Fig. 3, to hold the door securely from opening. Its position is shown in Fig. 2 and is also shown by dotted lines in Fig. 3. A spring 36A may be provided to start the door open when it is un- 50 locked.

Before proceeding with the description of the rest of the apparatus and the electrical circuits, I will describe the operation of the door lock.

55 When the parts are in the position shown, the lock serves the purpose of securing the door in its closed position. Now when a person turns one of the knobs 31 and thereby raises the latch 32, the latter is raised out of 60 engagement with the locking plate 39 but the door still remains locked because the latch 32 will be behind the locking roller 34. This locking roller is held from movement in either direction by the stop 34E and by the 65 swinging locking plate 35. If, however, a

current of electricity is passed through the magnet 36 the latter will become energized and will pull the locking plate 35 out of engagement with the bell-crank lever 34A which supports the locking roller 34. Now 70 the door may be opened because a pull on the knob 31 will cause the latch to push the locking roller back out of its way as the roller will then be free to swing about the pivot 34B. When the latch is raised it will cause the 75 bridge pieces 37F to be moved down onto contacts 37D as I have already shown, and when the door is opened the contact face 32F of the latch 32 will break the contact it has made between the stationary contacts 80 38A and 38B. The stationary locking plate 39 may be so arranged that when a person lifts the latch up out of engagement with it and thereby causes the contacts 37D to be connected, that the upper edge of the plate 39 85 will support the latch in this raised position and it will then remain in that position until the door is either opened or pushed shut.

Fig. 1 shows what I have called a "floor controller" 17 mounted upon the top of the 90 motor 13. A side elevation of this floor controller is shown in Fig. 7. It comprises a stand 17A which supports the various parts of the mechanism. A shaft 17B rigidly supports a series of arms 17C, the outer ends of 95 which carry antifriction rollers 17D. This shaft is arranged to be rotated by some moving part of the hoisting mechanism as for example by having a chain-wheel 17E connected with the shaft of the winding-drum 14 by 100 a chain 18. This is for the purpose of causing the arms 17C to have a movement proportional to that of the elevator car 10. Another shaft 17F carries a series of contact arms 17G, 17G', loosely mounted upon it. 105 These are arranged to make contact with and electrically connect in pairs either one of two series of stationary insulated contacts. The upper series of these contacts are designated by 40 on one side and by 41 110 on the opposite side, while the two lower series of these contacts are designated by 42 and 43. The inner ends 17H of the contact arms 17G, 17G' are cam-shaped and are so arranged that the contact arms are moved into 115 engagement with either the upper or lower series of stationary contacts on their respective sides by the arms 17C. The further operation of this device will appear later in connection with the description of the electrical 120 circuits which it is adapted to control.

Referring now to Fig. 6, I will trace the various circuits there shown and at the same time describe the operation of the apparatus and the automatic elevator system which I 125 have invented. The main circuits are shown by heavy lines while all the auxiliary controlling and operating circuits are shown by light lines. The mains are shown at the top of the figure designated by + and -. They 130

are shown passing through fuses and a main line switch to certain contacts of a reversing switch 50. The plus main is connected to contacts 50A and 50B, and the minus main is connected to a contact 50C. Contacts 50D and 50E are connected together. The contacts 50C, 50D and 50E are mounted upon but insulated from a movable support designated by dotted lines and are arranged to be moved together either against contacts 50G, 50F and 50A or against contacts 50I, 50H and 50B, respectively. This may be done by energizing either the electromagnet 50J or the electromagnet 50K. The motor armature is designated by 13A. One of its brushes is connected with contacts 50H and 50G and its other brush is connected with contacts 50I and 50F. One side of the shunt field 13B of the motor and the winding 16A of the brake is connected to contacts 50D and 50E and their other side is connected to the minus main. Now when the reversing switch is moved to one side or the other, it is evident that an electric current will pass through the motor armature in one direction or the other, and that a current will also pass through the shunt field and the magnet winding and this will cause the motor to rotate in one direction or the other and through its connected mechanism to drive the elevator car up or down. The car will continue to run in the same direction until the movable contacts of the reversing switch are again brought back to central position which will cut off the current supply from the motor and brake and cause the car to stop. I will now trace the controlling circuits and show how the motor and car may be automatically started and stopped. A conductor 60+ is connected to the + main near contact 50B and runs from there through a slack-cable switch 61 (which is well known in the art and therefore will not be described here) to the contact 38B in the first door lock. If this is now connected with its companion contact 38A by the metallic face 32F on the latch 32 the circuit will be continued through this lock to the next one and so on through the whole series of locks. This can only happen when all of the hatchway doors are closed and locked. After this part of the circuit 60+ has passed through all of the locks it branches and one part of it, 62+, goes to the car. It there runs through a gate contact 63 which is arranged to be closed only when the gate or door on the elevator car is closed, through a safety stop button 64 and thence by a conductor A+ to one terminal of a double-wound non-interference relay 70. The circuit then extends through both of the windings of relay 70 and by a conductor B+ to a series of push-buttons on the car and to one of the contacts 37D in each of the door locks. The windings on relay 70 are opposed to each other so that a current passing through one

of them will neutralize the effect of a current passing through the other, but a current passing through either of them alone will energize the magnet of the relay and cause it to open its contacts. Another conductor C+ runs from a point between the two windings of relay 70, to movable contacts on floor relays 1A, 2A and 3A.

If an operator in the car presses one of the buttons in the car, let us for example say the middle one, he will thereby close a circuit through the conductors just described and through conductor 2 to the winding 2A of a floor-relay, through this floor-relay winding to one of the series of stationary contacts 40 and also to one of the series of stationary contacts 41 on the floor controller, through an adjacent contact on the floor controller, and thence through either conductor U or D to magnet 50J or 50K, through conductor 4, winding of a relay 72, to the negative or -line. This will cause the reversing switch to be closed on one side or the other in the manner before described and cause the car to travel up or down.

I will now show why the circuit will be closed through either U or D through the floor controller contacts. I have shown in connection with Fig. 7 that these contacts are opened or closed by the arms 17C which move in proportion to the movement of the car. They are usually geared down to have but a short travel. When the car moves down below the second floor one of the arms 17C opens the contacts at 41A and closes those at 43A, and when it reaches the upper floor it opens contacts at 41B and closes contacts at 43B. Contacts at 40A and 40B will be closed and contacts at 42A and 42B will be open. These operations are so adjusted that the contacts for a given floor are opened and closed as the car reaches that floor. The contact arms 17G, 17G' are thus actuated by the movement of the car. In order that they cannot be moved by hand and thus tampered with I prefer to extend their cam faces 17H, 17H' around the path of movement of the roller 17D as shown in Fig. 8. In this case if roller has been moved to the right by the movement of the car, the arm 17G will be moved down thereby and locked in the position designated by dotted lines until 17D is moved back again to the left.

Referring again to Fig. 6 it will be seen that when the car is above the second floor the only path for the conductor from floor relay 2A will be through contacts at 40B to magnet 50K through conductor D. This will close the reversing switch 50 in such a way as to cause the car to run down until it reaches the second floor, when contacts at 40B will be opened and contacts at 42B will be closed. This will open the reversing switch, and stop the car.

As the current which passes through the reversing switch magnet passes also through relay magnets 2A and 72, they will become energized. 2A supplies current to the reversing switch magnet from the positive line in a well known manner so that the operator need not hold the car push-button closed and at the same time this cuts off the right hand winding of the non-interference magnet 70, causes that to be energized and thereby cuts off the supply through conductor B+ to the car push buttons and to contacts 37D in the door locks. The magnet 72 will also be energized and will break a contact at 72B which will cut off the supply through conductor 72A to the series of contacts 42 and 43 on the floor controller and to the door lock magnets 36 on all of the floors.

After one of the hatchway doors or the elevator car gate has been opened, the circuits will be inoperative until the door or gate has been closed and locked again because the supply through conductor 60+ will be broken between one pair of the door contacts 38A, 38B. If only the gate contact 63 is opened this will not interfere with the operation of the lock. This part of the operation from the car is similar to that of a well known system of control for automatic electric elevators. In the same way as above described the other buttons in the car may be pushed to send current through conductors 1 or 3 and floor-relays 1A or 3A to cause the car to move to a corresponding floor.

The contacts 37D in each of the door locks are arranged to be connected by a contact plate 37F, and the parts just mentioned form a circuit closer which is in the controlling circuits in such a way that when one of them is actuated to close its circuit it will cause the car to come to the floor at which it is situated. Let us for example consider that a person turns the latch at the second or middle floor. If the car is at that floor, the door-lock magnet will be energized thereby, but if it is not at that floor, a circuit will be established through conductor 2, floor relay 2A, floor controller contacts at 41A or 42B, through the U or the D wire to and through magnets 50J or 50K and through magnet 72 to the - line. This will cause the reversing switch to close and the car to move until it reaches the particular floor at which the lock was moved when it will be stopped automatically by the action of the floor controller 17. Thus the contacts 37D and contact plate 37F perform the function of push buttons in some of the systems now in use. It is only necessary; however, according to my invention, for a person to try the door lock, to cause the car to come to the floor where the lock was tried. I have before stated that the locking plate 39 may be so placed in relation to the locking roller 34 and the latch 32, that

it may hold the latch up in its raised position 65 after it has been raised by a person outside the door. This of course would maintain the contacts 37D closed and therefore maintain the current in the circuit through the reversing switch until the car comes to that 70 floor, and thereby interrupts the circuit at the floor controller. The floor relays 1A, 2A and 3A are for the purpose of maintaining such current when push buttons are used and therefore are not necessary when the 75 locking plate is arranged to do the same thing.

At the same time contacts 37D are closed, contacts 37D' are also closed. These are in the circuit of the locking magnets 36 and this circuit extends from each locking magnet 80 through conductors 1D, 2D and 3D to the contacts in series 42 and 43 on the floor controller. These "back" contacts on the floor controller will only be closed when the car is at their corresponding floor. Now to show 85 the operation of these locking magnet circuits I will trace one of them in detail. One of the contacts 37D' at each floor is connected with the + main by conductor 63+. Now if contact plate 37F at the second floor, for example, is moved against its contacts 37D', a circuit may thereby be established through conductor 2D, floor controller contacts at 43A and at 42B, through the arm 72A and contact at 72B to the - main. In order to establish such a circuit both the floor controller contacts at 43A and at 42B must be closed and the contact at 72B must be closed. This means that the car must be at the second floor and that the reversing switch 50 must 90 be open so that the car is stopped. If these conditions are present the locking magnet 36 at the second floor will be energized and the door may be opened. The operation is similar for the other floors, only the circuit will be 95 closed through conductors 1D and contacts at 42A for the first floor, or 3D and contacts at 43B for the third floor. If the car is not present at a given floor when the latch is 100 moved to close the contacts of the door-lock 105 magnet circuit, the closing of these contacts will not complete the circuit but will only close the gap in the circuit which will still be open at the floor controller. A movement of 110 the car to the desired floor will cause the floor controller to be actuated to complete the door-lock magnet circuit and to thereby release the door.

The object of magnet 72 will now be apparent, for this magnet is energized and breaks the door lock circuit at 72B whenever the reversing switch is closed. This makes it impossible for one to unlock any of the hatchway doors while the car is running and therefore prevents one opening a door while the 125 car is passing. Instead of a magnet 72 for this purpose, contacts may be provided on the reversing switch itself for this purpose.

The separate magnet is a preferred construction as it is readily applied to installations already in use.

In elevators of this class it is customary to 5 add many refinements such as automatic accelerating devices, series fields for the motors, automatic limit stops and many others. These are no part of the present invention and therefore I have omitted them from the 10 drawings and description and have shown only such parts as are necessary to describe and illustrate the use of my invention.

I believe many features of this invention are broadly new and that therefore my invention should not be limited to the specific 15 devices shown and described as illustrative of the invention.

If one of the latches 32 is held up by its locking plate 39 until the car comes to its 20 floor, the door will be immediately pushed open by spring 36A and will break the operating circuit between contacts 38A and 38B, and thus prevent any one at some other floor 25 from calling the car away from the person who has first called it.

This invention is applicable to any form of elevator which is electrically controlled and is not necessarily confined to electric elevators.

30 What I claim is:

1. The combination with an electrically controlled elevator, a door lock, and means for starting the elevator upon a movement of a portion of said lock.

35 2. The combination of an electrically controlled elevator, a controlling circuit therefore, and a door lock having contacts in the controlling circuit to arrange to cause the elevator to be started when said contacts 40 are closed.

45 3. The combination of an electrically controlled elevator, a controlling circuit therefore, and a door lock having contacts in the controlling circuit so arranged that they will start the car upon movement of a portion of the lock.

50 4. In an electrically controlled elevator, the combination of controlling circuits, a car, a hatchway in which the car runs, a door in the hatchway, a lock on said door, and contacts in the lock connected to the controlling circuits and arranged to cause the elevator to be started when said contacts are closed.

55 5. In an electrically controlled elevator, the combination of controlling circuits, a car, a hatchway in which the car runs, a door in the hatchway, a lock on said door, and contacts in the lock connected to the controlling circuits and arranged to cause the car to 60 move to said door upon a movement of a portion of said lock.

65 6. In an electrically controlled elevator, the combination of controlling circuits, a car, a hatchway in which the car runs, a door in

the hatchway, a lock on said door, and contacts in the lock connected to the controlling circuits, some of which are arranged to cause the car to move to said door and others of which are arranged to render the controlling circuits inoperative.

70 7. In an electrically controlled elevator, the combination of controlling circuits, a car, a hatchway in which the car runs, a door in the hatchway, a lock on said door, contacts in the lock connected in the controlling circuits some of which are arranged to cause the car to move to the door when a portion of the lock is moved, and others of which are arranged to render the controlling circuits inoperative when the door is opened.

75 8. In an electrically controlled elevator, the combination of controlling circuits, a car, a hatchway in which the car runs, a plurality of doors in the hatchway, a lock on each door, contacts in the locks connected in the controlling circuits which are arranged to cause the car to move to any given door when a portion of its lock is moved.

80 9. In an electrically controlled elevator, the combination of controlling circuits, a car, a hatchway in which the car runs, a plurality of doors in the hatchway, a lock on each door, contacts in the locks connected in the controlling circuits some of which are arranged to cause the car to move to any given door when a portion of its lock is moved and others of which are arranged to render the controlling circuits inoperative when any door is opened.

85 10. The combination of an electrically controlled elevator, a car, a door lock, means for starting the elevator upon a movement of a portion of the lock, and means dependent upon the position of the car for releasing the lock.

90 11. The combination of an electrically controlled elevator, a controlling circuit therefore, a car, a door lock having contacts in the controlling circuit for controlling the elevator, and electrical means dependent upon the position of the car for releasing the door lock.

95 12. In an electrically controlled elevator, the combination of controlling circuits, a car, a hatchway in which the car runs, a door in the hatchway, a lock on said door, contacts in said lock connected to the controlling circuits arranged to cause the car to move to said door upon a movement of a portion of the lock, and electrical means for releasing the lock when the car has reached the door.

100 13. In an electrically controlled elevator, the combination of controlling circuits, a car, a hatchway in which the car runs, a door in the hatchway, a lock on said door, contacts in the lock some of which are arranged to cause the car to move to the door and others of which are arranged to render the controlling circuits inoperative, and electrical means

for releasing the lock when the car has stopped opposite the door.

14. In an electrically controlled elevator, the combination of controlling circuits, a car, 5 a hatchway in which the car runs, a plurality of doors in the hatchway, a lock on each door, contacts in the locks connected in the controlling circuits which are arranged to cause the car to move to any given door when 10 a portion of its lock is moved, and electrical means for releasing the lock when the car has stopped opposite the given door.

15. In an electrically controlled elevator, the combination of controlling circuits, a car, 15 a hatchway in which the car runs, a plurality of doors in the hatchway, a lock on each door, contacts in the locks connected in the controlling circuits which are arranged to cause the car to move to any given door when 20 a portion of its lock is moved, and electrical means dependent upon the position of the car and the position of the lock for releasing the lock.

16. In an electrically controlled elevator, 25 the combination of controlling circuits, a car, a hatchway in which the car runs, a plurality of doors in the hatchway, a lock on each door, a magnet in each lock, contacts in the locks some of which are in the controlling 30 circuits and are arranged to cause the car to move to any given door when a portion of its lock is moved, others of which are in circuit with the magnet, and means for energizing said magnet and thereby releasing the lock 35 when the latter contacts are closed.

17. In an electrically controlled elevator, the combination of controlling circuits, a car, a hatchway in which the car runs, a plurality of doors in the hatchway, a lock on 40 each door, a magnet in each lock, contacts in the locks some of which are in the controlling 45 circuits and are arranged to cause the car to move to any given door when a portion of its lock is moved, others of which are in circuit with the magnet, means for energizing said magnet and thereby releasing the lock when the latter contacts are closed when the lock is moved, and means for preventing such energizing of said magnet except when the 50 car has stopped at such given floor.

18. In an electrically controlled elevator, the combination of controlling circuits, a car, a hatchway in which the car runs, a plurality of doors in the hatchway, a lock on each 55 door, a magnet in each lock, contacts in the lock some of which are in the controlling circuits and are arranged to cause the car to move to any given door when a portion of its lock is moved, others of which are in circuit 60 with the magnet, means for energizing said magnet and thereby releasing the lock when the latter contacts are closed, when the lock is moved, means for preventing such energizing of said magnet except when the car 65 has stopped at such given floor, and means

for rendering the controlling circuits and the door lock magnets inoperative when any one of the doors is opened.

19. In combination with an electrically controlled elevator, a floor controller having 70 a double set of contacts, and means actuated by the movement of the elevator for opening one set of contacts and at the same time closing the other set of contacts.

20. In an electrically controlled elevator 75 the combination of a car, a hatchway in which the car is adapted to run, an opening in the hatchway at a landing, and a floor controller having a double set of contacts and means actuated by the movement of the elevator for opening one set of contacts and closing the other set of contacts, as the car 80 approaches the opening.

21. In combination with an electrically controlled elevator, a car, a floor controller 85 having two sets of contacts, a contact arm for engaging with one or the other of said sets of contacts, an actuating lever arranged to have a movement proportional to that of the car and to move the contact arm from 90 one set of contacts to the other set of contacts when the car reaches a predetermined point in its travel.

22. In combination with an electrically controlled elevator, a car, a floor controller 95 having two sets of contacts, a contact arm for engaging with one or the other of said sets of contacts, an actuating lever arranged to have a movement proportional to that of the car and to move the contact arm from 100 one set of contacts to the other set of contacts when the car reaches a predetermined point in its travel, and means for locking the contact arm in its moved position.

23. In combination with an elevator, a 105 car, a hoisting machine, a hatchway in which the car runs, a plurality of doors in the hatchway, a lock for each door, and a single floor controller directly connected with and actuated by the hoisting machine and arranged to control all of said locks.

24. In combination with an elevator, a car, a hoisting machine, a hatchway in which the car runs, a plurality of doors in the hatchway, a lock for each door, and a single 115 floor controller directly connected with and actuated by the hoisting machine and arranged to control all of said locks and the movement of the car.

25. In combination with an elevator, a 120 car, a hoisting machine, a hatchway in which the car runs, a plurality of doors in the hatchway, a lock for each door, a single floor controller directly connected with and actuated by the hoisting machine and arranged to control all of said locks, and means for preventing the releasing of the locks when the car is passing a door.

26. In combination with an electrically controlled elevator, a hoisting mechanism, a 130

car, a hatchway in which the car runs, a plurality of doors in the hatchway, a lock on each door, contacts in the locks, a floor controller connected to the hoisting mechanism, 5 contacts on the floor controller, circuits between the floor controller and the door lock contacts, and electrical means for releasing the door locks when the door lock contacts are closed and the floor controller contacts 10 are closed.

27. In combination with an electrically controlled elevator, a hoisting mechanism, a car, a hatchway in which the car runs, a plurality of doors in the hatchway, a lock on 15 each door, contacts in the locks, a floor controller connected to the hoisting mechanism, contacts on the floor controller, circuits between the floor controller and the door lock contacts, and electrical means for releasing 20 the door locks when the door lock contacts are closed and the floor controller contacts are closed and the car is at rest.

28. In combination with an electrically controlled elevator, a car, a hatchway door, a lock for the door, a floor controller having two sets of contacts one of which sets is arranged to automatically stop the car at the door and the other of which sets is arranged to release the door lock.

30. 29. In an electrically controlled elevator, the combination of controlling circuits, a car, a floor controller arranged to have a movement proportional to that of the car, a hatchway in which the car runs, a plurality of 35 doors in the hatchway, a lock on each door, contacts in the locks connected in the controlling circuits which are arranged to cause the car to move to any given door when a portion of its lock is moved.

40. 30. In an electrically controlled elevator, the combination of controlling circuits, a car, a floor controller arranged to have a movement proportional to that of the car, a hatchway in which the car runs, a plurality of 45 doors in the hatchway, a lock on each door, contacts in the lock connected in the controlling circuits some of which are arranged to cause the car to move to any given door when a portion of its lock is moved and others of which are arranged to render the controlling circuits inoperative when any door is opened.

31. In an electrically controlled elevator, the combination of controlling circuits, a car, 55 a hatchway in which the car runs, a plurality of doors in the hatchway, a lock on each door, contacts in the lock connected to the controlling circuits and arranged to cause the car to move to a given door upon a movement of a portion of its lock, a floor controller

arranged to have a movement proportional to that of the car and to automatically stop the car when it has reached the given door and to automatically release the lock when the car has stopped at the door. 65

32. In an electrically controlled elevator, the combination of controlling circuits, a car, a hatchway in which the car runs, a plurality of doors in the hatchway, a lock on each door, contacts in the lock connected to the 70 controlling circuits and arranged to cause the car to move to a given door upon a movement of a portion of its lock, a floor controller arranged to have a movement proportional to that of the car and to automatically stop 75 the car when it has reached the given door and to automatically release the lock when the car has stopped at the door, and means situated in the car for controlling its movement. 80

33. In an electrically controlled elevator, the combination of controlling circuits, a car, a hatchway in which the car runs, a plurality of doors in the hatchway, a lock on each door, contacts in the lock connected to the 85 controlling circuits and arranged to cause the car to move to a given door upon a movement of a portion of its lock, a floor controller arranged to have a movement proportional to that of the car and to automatically stop 90 the car when it has reached the given door and to automatically release the lock when the car has stopped at the door, and other contacts in the door-locks arranged to render the controlling circuits and the door lock releasing device inoperative when one of the doors is open. 95

34. In an electrically controlled elevator, the combination of controlling circuits, a car, a hatchway in which the car runs, a plurality 100 of doors in the hatchway, a lock on each door, a magnet in each lock, contacts in the locks some of which are in the controlling circuits and are arranged to cause the car to move to any given door when a portion of its 105 lock is moved, others of which are in circuit with the magnet, means for energizing said magnet and thereby releasing the lock when the latter contacts are closed, and a floor controller arranged to have a movement proportional to that of the car and to automatically govern the controlling circuits and the door lock magnets. 110

In testimony whereof, I have signed my name to this specification in the presence of 115 two subscribing witnesses.

WILLIAM D. LUTZ.
